UNITED STATES PATENT OFFICE.

GIACINTO ROSSI, OF PHILADELPHIA, PENNSYLVANIA.

DESIGN FOR A COMBINED LAMP, TELEPHONE, AND SMOKING STAND.

Application filed December 16, 1925. Serial No. 15,773. Term of patent 14 years.

To all whom it may concern:

Be it known that I, GIACINTO ROSSI, a citizen of the United States, residing at Philadelphia, in the county of Philadelphia and State of Pennsylvania, have invented a new, original, and ornamental Design for a Combined Lamp, Telephone, and Smoking Stand, of which the following is a specification, reference being had to the accompanying drawings, forming part thereof.

I claim:

The ornamental design for a combined lamp, telephone, and smoking stand, as shown.

GIACINTO ROSSI.
